(57) **CLAIM**

I claim the ornamental design for a landing gear crank adapter, as shown and described.

DESCRIPTION

FIG. 1 is a perspective view of a landing gear crank adapter showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a rear elevational view thereof; and,

FIG. 7 is a front elevational view thereof.

The broken lines of FIGS. 1, 2, 6, and 7 are for the purpose of illustrating environmental structure and form no part of the claimed design.
